COMBINATION BED AND COUCH

Robert W. Limpus, New York, N. Y.

Application June 7, 1949, Serial No. 3,095

Term of patent 14 years

(Cl. D5—4)

To all whom it may concern:

Be it known that I, Robert W. Limpus, a citizen of the United States of America, residing in the city of New York, in the county of New York and State of New York, have invented a new, original, and ornamental Design for a Combination Bed and Couch, of which the following is a specification, reference being had to the accompanying drawing, forming a part hereof:

The figure is a perspective view of the combination bed and couch embodying the new design. In this figure one of the drawers is shown as it appears in extended position and the other side of the design, including the headboard, is similar to that shown.

I claim:

The ornamental design for a combination bed and couch, substantially as shown and described.

ROBERT W. LIMPUS.
